UNITED STATES PATENT OFFICE.

EDWIN E. BARNEY, OF NEW ROCHELLE, NEW YORK, ASSIGNOR TO REMINGTON TYPE-
WRITER COMPANY, OF ILION, NEW YORK, A CORPORATION OF NEW YORK.

TYPEWRITING MACHINE.

Application filed January 5, 1924. Serial No. 684,548.

My invention relates to escapement mechanism for typewriting machines, and its general object is to provide new and improved mechanism which shall promote regular and even step-by-step feeding movements of the carriage under all conditions, doing away with the irregularities and defects in feeding which result in imperfect typewritten matter.

To the above and other ends which will hereinafter appear, my invention consists in the features of construction, combinations of devices and arrangements of parts hereinafter described and particularly pointed out in the claims.

The preferred form of my invention is illustrated in the accompanying drawings, wherein—

Figure 1 is a fragmentary, front-to-rear, vertical skeletonized view illustrating my new improved escapement mechanism; and trains of devices for operating it comprising the type action, universal bar and space bar train of the No. 10 Remington typewriting machine as adapted to my invention.

Figure 2 is a view corresponding to Figure 1 but omitting some parts disclosed therein and showing other parts in different relationships.

Figures 3-6 are diagrammatic views illustrating different stages of the escapement operation.

Figure 7 is a fragmentary vertical sectional view taken on a plane indicated by the section line 1-1 in Figure 1 and looking rearward.

Figure 8 is a fragmentary vertical sectional view taken on the section line 2 in Figure 1 and looking rearward in the direction of the arrow at said line.

Figure 9 is an enlarged fragmentary horizontal sectional view taken axially of the escapement wheels.

Figure 10 is a fragmentary vertical sectional view taken on the section line 3-3 in Figure 9 and looking in the direction of the arrow at said line.

Figure 11 is a perspective view showing certain parts of my novel escapement mechanism, the parts being separated for the sake of clearness.

Escapement mechanisms as heretofore constructed have been liable to cause irregularity or imperfection in the feeding of the carriage due primarily to rapid or uneven

operation of the keys of the typewriting machine, such irregularity resulting in imperfect typewriting. One of the common defects in typewritten matter is what is termed a "spread", meaning the printing of a character in what should be the space between two words. Various theories have been advanced to account for this result. It is believed to be due to rapid operation of the space bar such that the impulse of the space bar is communicated to the escapement mechanism before the mechanism has had opportunity to return to normal condition following the preceding stroke under impulse of a printing key. Ordinarily, the escapement mechanism is set so as to afford release or escapement of the carriage as soon as possible after the printing takes place. The result is that there is a zone or field in which the type bar moves away from the printing point after striking and before the escapement takes place or is completed; and it is while the type bar is in this comparatively narrow zone or field that an operation of the spacing bar may take place without effecting a corresponding escapement movement or letter spacing feeding of the carriage. Consequently the first letter of the next word following the actuation of the space bar will be printed immediately following the last letter of the preceding word, and without leaving a space between them. It is primarily to obviate or prevent such defective operations and other defective operations that I have devised my new and improved escapement mechanism.

In carrying out my invention in the present instance, I provide a double escapement mechanism or two escapement mechanisms, each complete in itself and comprising an escapement wheel and a dog carrier mounting a pair of dogs, the dog carriers or rockers being controlled by separate key actuated trains, one controlled by the type bars and the other by the space bar.

The escapement wheels are connected by differential or planetary gearing comprising two beveled gears, each connected with an escapement wheel and both meshing constantly with a beveled pinion that is mounted on a support pivoted coaxially with the beveled gears, the escapement wheel and the usual feed pinion of the machine, and caused to turn with the said feed pinion. When one

of the dog rockers is actuated it frees the associate escapement wheel, which is turned by the beveled pinion, said pinion being forced to rotate on its own axis by reason 5 of its connection with the other beveled wheel which remains fixed.

The beveled pinion at the same time revolves bodily about the common axis, as its support is turned by the feed pinion. When 10 the other dog rocker is actuated by its train the reverse action will occur; that is, the other escapement wheel will be caused to turn through the differential gearing, the beveled pinion acting as before but the action 15 of the associate beveled gears being reversed. The construction is such that the effective and regular step-by-step feeding of the carriage will not be interfered with should one of the escapement operations effected by one train, not have been completed before the other escapement mechanism be actuated.

It is to be understood that while the differential gearing is the best form of connection at present known to me for obtaining my improved results, nevertheless other forms of connections may be employed, one of such being shown in my application Serial No. 690,382, filed Feb. 4, 1924.

Referring specifically to the present embodiment of my invention, the Remington typewriting machine to which it is shown as applied has a main frame comprising a base portion 1 and a top plate 2, which are fragmentarily shown in Figure 1. Supported above the top plate is a carriage comprising a truck 3 having front and rear bars and connecting end bars. The carriage supports a platen 4 diagrammatically illustrated and is connected through antifriction rollers 5 with front and rear guide rails fixed above the top plate, the rear guide rail 6 being shown in Figure 1. Co-operative with the front face of the platen are type bars 7 pivoted at 8 on a type bar support or segment 9 and normally supported near their free ends on a type rest 10. The rear end portion of each type bar is provided with a slot 11 co-operative with which is an actuating pin 12 projecting laterally from a sublever or bell crank 13, the set of sublevers being pivoted at 14 on a stationary bracket 15 mounted in the base portion 1 of the main frame. The short arm of each sublever is formed with a slot 16 which cooperates with a pin 17 projecting from a key lever 18. The set of key levers 18 are pivoted at their rear end portions on the fulcrum 19 and at their front ends are provided with key caps 20. When any key 20 is depressed, it operates through the described train of connections to actuate the connected type bar, swinging it upward and rearward to printing contact with the front face of the platen. 60 Each type bar has a contact face 21 which

as it nears the platen strikes against the front edge of a curved universal bar 22 which is seated in a depression 23 formed in the rear face of the type bar segment 9. The universal bar 22 is part of a universal 70 bar frame which further comprises rearwardly extending arms 24 and a lug 25 carrying a guide pin 26 which slidably engages in a hole 27 in the segment and thus assists to support the front portion of the universal bar frame. The rear portion of said frame is supported on a rocking frame comprising a rock shaft 28 which is pivoted on a bracket 29 carried by the segment 9. Rising from the shaft 28 are arms 30, the two 75 end arms being pivotally connected with and supporting the arms 24. The middle arm 30 is bifurcated at its top as shown and carries a cross pin 31 which is engaged by the slotted forward end of a link 32 which extends rearward and provides a connector 80 between the key actuated universal bar frame and escapement devices hereinafter described.

The usual space bar or key 33 is arranged 90 at the front of the keyboard comprising the banks of printing keys 20 and is supported on the front ends of spacing lever arms 34 which project forward from a rock shaft 35. Secured about centrally to said rock 95 shaft and projecting upward and rearward therefrom is an arm 36 which carries an extension arm 37 provided with a headed actuating pin 38 projecting laterally from its upper end. The arm 37 is adjustably supported on the arm 36, its lower end being pivoted at 39 to said arm 36 and a clamping screw 40 being adapted to hold it in various pivotal relationships. The clamping screw 40 engages in a cross slot 41 in the arm 37 which also is formed with an elongated hole 42 engaged by an eccentric screw 43 carried by the arm 36. By loosening the screw 40 and turning the screw 43 the arm 37 may be readjusted to vary the position of the pin 38. The parts hereinbefore described correspond with those found in the Remington typewriting machine.

Carried by a frame 44 pivoted at 45 on the carriage is a feed rack 46 that is normally maintained in spring-pressed engagement with an elongated feed pinion 47 having ratchet-like teeth and mounted loosely on the front end portion of a horizontally disposed and rearwardly extending shaft 48. (Figs. 115 1, 8 and 9). The shaft 48 is carried by a support or bracket comprising a U-shaped or yoke portion 49 and a central standard 50. Extending downward through the standard are screws 51, which are threaded at their lower ends into a shelf-like portion 52 of a U-shaped main bracket 53 having side tabs or ears 54 that receive screws 55 whereby the main bracket 53 is secured to the under side of the top plate 2. The top plate is 120 125 130

cut away as indicated at 2^a between the side portion of the bracket 53 to afford space for certain escapement devices. The standard 50 rises through the cutaway 2^a at one side thereof and the side portions of the yoke 49 terminate at about the middle of this cut-out portion and over the central part of the main bracket 53. The front terminal portion of the yoke 49 receives a headed and shouldered bearing screw 56 which engages in a bearing hole 57 in the front end of the shaft 48. The rear end of said shaft is likewise formed with a bearing hole 58 which receives the reduced forward end of a bearing pin 59 that is adjustably secured by a screw 60 in the rear terminal portion of the yoke 49. The construction is such that the shaft 48 may turn freely on its end bearings 56 and 59 while the elongated pinion 47 may turn freely on the shaft. The platen carriage is power driven, being connected by a band or strap 61 with the usual spring drum or carriage motor 62, and it will be understood that the carriage power will be transmitted through the rack 46 to the feed pinion 47. Means are provided for causing said pinion when rotated in one direction to transmit motion to the shaft 48, said means comprising a pawl 63 which is pivoted at 64 to a disk 65 arranged behind the pinion 47 and having a hub 66 which receives a cross pin 67 passing through the shaft 48 (Figs. 1, 9, and 10) and fixing the disk thereto. The pawl 63 has secured in it one end of a wire spring 68, said spring being anchored to pins 69 projecting from the front face of the disk 65. The spring tends constantly to maintain the toothed end of the pawl 63 engaged with the teeth of the feed pinion 47, and, as will be clearly understood from Fig. 10, the disposition of the pawl tooth to the pinion teeth is such that when the pinion is turned in letter-feeding direction, as indicated by the arrow in Figure 10, the motion will be transmitted through the engaged pinion teeth to the pawl 63 and through it to the disk 65 and the shaft 48. On the other hand, during return or rightward movements of the carriage, and the consequent turning of the pinion in the opposite direction from that indicated by the arrow, the spring pressed pawl 63 will click idly over the pinion teeth, leaving the disk 65 and the shaft 48 unaffected by the rotation of the pinion.

Supported on the shaft 48 are a pair of circular racks or toothed escapement wheels 70, 71, provided respectively with teeth 72 and 73, the escapement wheels generally resembling the usual escapement wheels of the machine but the teeth being spaced further apart so that there are approximately half the usual number of teeth for each of the escapement wheels 70 and 71. The escapement wheel 70 is disposed behind the wheel 71 and has arranged at its front face a bevel gear wheel 74 which is provided with a hub 75 that projects rearward through the escapement wheel 70. Said escapement wheel and said gear wheel 74 are rigidly connected or secured together by screws 76, and the hub 75 which loosely surrounds and bears on the shaft 48 serves both of the escapement wheel and the gear wheel. The member comprising the wheels 70 and 74 is prevented from rearward displacement on the shaft 48 by a collar 77 which is secured to the rear end of the shaft by a set screw 78. The escapement wheel 71 is arranged close behind the disk 65, and, secured to the rear of the wheel 71 by screws 79, is a beveled gear wheel 80, having a hub 81 which fits loosely on the shaft 48 and serves both for the escapement wheel 71 and the gear wheel 80, the front of the hub 81 being contiguous to the rear of the hub 66. It will be observed that the teeth of the gear wheels 74 and 80 are oppositely disposed and face each other. Secured to the shaft between these gear wheels is a supporting member or arm 82 which is shown detached in Fig. 11. The carrier or member 82 comprises a hub portion 83 which surrounds the shaft 48, said hub portion being split as indicated at 84 and being provided at opposite sides of the split with lugs 85 which receive a clamping screw 86 that is adapted when tightened to clamp the member 82 fixedly to the shaft 48. The upstanding portion 87 of the member 82 projects radially from the shaft and is formed longitudinally with a hole 88 that receives a headed bearing pin 89 having a shouldered portion which projects outside the arm 87 and provides a bearing for a beveled pinion 90. Said pinion 90 rests on the portion 87 and is adapted to turn freely on the pin 89 and constantly intermeshes with the gear wheels 74 and 80. The bearing pin 89 is fixed in place by a cross pin 89^a. The construction is such that the end portions of the hub 83 are contiguous to the hubs 75 and 81 and prevent displacement of the gear wheels and escapement wheels towards each other along the shaft 48.

It will be understood that if one of the escapement wheels be held against movement while the other is released, the associate gear wheel of the stationary escapement wheel will act as a fixed track along which the pinion 90 will move as its support 82 rotates with the shaft or axle 48. At the same time the pinion will rotate on its axis 89 and this movement of rotation will be transmitted to the released escapement wheel through its associate gear wheel. In other words by alternately holding and releasing the escapement wheels they will be adapted to transmit and receive feeding motions from the feed rack and pinion. Also it will be understood that if both escapement wheels be released at the same time they will

both be turned through their connection with the pinion or actuating device 90, said pinion during such turning movements of the escapement wheels not rotating on its own axis 89^a but merely serving to transmit the movement of rotation of the support 82 to the members or intermeshing gear wheels 74 and 80, these constituting in effect what may be termed a train of differential gearing. It will be observed that the gear train, together with the escapement wheels and the feed pinion 47, are mounted on the bracket 49, 50 and may be detached as a unit therewith.

15 The means for controlling the pair of escapement wheels so that they may be released and held as desired is constituted by dog or detent mechanism, comprising in the present instance a pair of dog carriers or 20 rockers each provided with a pair of dogs and mounted on the main bracket 53 so as to be detachable as a unit therewith. It is to be noted that the whole double escapement mechanism, comprising the escapement wheels, dog rockers and associate parts, 25 may be detached as a single unit, for all of these parts being mounted on the bracket 53, are removable with it when the screws 55 are removed.

30 The two dog rockers are supported on the detachable bracket 53 below their associate escapement wheels and are mounted on axes transverse of the axes of the escapement wheels, said dog rockers being adapted to rock in opposite directions to effect escapement movements. The dog carrier or 35 rocker 91 of the rear escapement mechanism shown in Figs. 1, 2 and 8 is of the usual Remington construction, comprising a horizontally disposed body portion 92 from which rises an upright portion 93. The ends of the body portion 92 are formed with depressions which receive coned pivots 94 and 95 which project oppositely inward from the 40 sides of the bracket 53 and are adjustably fixed in place by securing devices 96 and 97. Pivoted at 98 on the front of the dog rocker 91 is an angular stepping dog 99, the upwardly extending arm of which terminates 45 in a tooth 100 that normally engages with one of the teeth 72 of the rear escapement wheel 70, said dog being normally held against a stop 101 on the rocker by the force of the carriage power transmitted through 50 the engaged tooth 72. The tail portion 99^a of the dog 99 has connected to it a dog spring 102, the lower end of the spring being connected to the dog and the upper end being anchored to the dog rocker. The dog 55 spring tends constantly to swing the dog 99 on its pivot 98 towards the left, said dog when released being free to move or step leftward until arrested by a stop 103 on the rocker. Secured to the rear face of the dog rocker 91 is a fixed dog 104 provided

with a beveled engaging portion 105 which is adapted to co-operate with the teeth 72 of the escapement wheel 70 when the dog rocker 91 is swung forward on its pivotal axis, 94, 95. Extending downward from the 70 dog rocker 91 at its rear side is an arm 106 which is provided at its lower end under the dog rocker axis with a laterally extending headed pin 107 which is engaged by the rear slotted end of the link or connector 32. 75 The construction is such that when the universal bar 22 is actuated by one of the type bars 7, the connector or push link 32 will be moved or thrust rearward, swinging the dog rocker 91 on its pivots and moving the 80 dog tooth 100 forward out of the escapement wheel 70 while bringing the beveled dog 104, 105, into engagement with said escapement wheel. As soon as the dog 99, 100 is thus released, it will be stepped leftward 85 by the spring 102 so that on the return swing of the dog rocker, the carriage will be allowed to move leftward a letter space distance. The rearward swing of the dog rocker is limited by the engagement of an 90 adjustable screw stop 108 carried by the dog rocker below its pivot, said screw stop projecting forward and being adapted to contact with an angular stationary stop 109 which projects upward and rightward from 95 the bottom of the bracket 53 and into the path of the stop 108 which as it swings rearward, will contact with the stationary stop 109 and arrest the dog rocker 91 in normal position. The rear movement of the dog 100 rocker is assisted by a rocker spring 110 which is connected at one end to the dog rocker 91 below its pivot, the opposite end of said spring being connected to the dog rocker of the front escapement mechanism 105 next to be described.

The second or front dog rocker 111 is shown in Figures 1, 2 and 7 and comprises a horizontally disposed body portion 112 and an upstanding portion or arm 113. At 110 its ends, the body portion is formed with depressions which receive the pointed ends of the supporting pivots 114 and 115, said pivots projecting inward from the side walls of the bracket 53 and being adjustably secured thereto by securing devices 116 and 117. Secured by screws 118 to the rear face of the upstanding portion 113 of the dog rocker 111 is a holding or fixed dog 119 terminating in an angularly disposed contact 115 portion or tooth 120. The tooth projects transversely of the escapement wheel 71 below the body thereof, and into the path of the wheel teeth 73 with one of which the dog tooth 120 normally engages across the 120 working face of said tooth. At the front side of the dog rocker 111 is pivoted at 121 a stepping dog 122 terminating in an engaging tooth 123 which is adapted to co-operate with the wheel 71 but normally lies 125

forward of the plane thereof. The tail 122^a of the dog 122 has connected to it the lower end of a dog spring 124, the upper end of said spring being anchored to the dog 5 rocker. Said spring acts normally to maintain the dog 122 engaged with a stop 125 projecting forward from the rocker, a second stop 126 being provided to limit the swing or stepping movement of the dog 122 10 towards the right. Extending downward from the dog rocker 111 below its pivot is an arm 127 to which is connected the forward end of the rocker spring 110. Said spring normally maintains an adjustable screw stop 15 128, which projects rearward from the dog rocker 111 below its pivot, in engagement with the front face of the stationary stop 109, as shown in Fig. 1.

The dog rocker 111 is adapted to be actuated or rocked rearward from the space key or bar 33, connection being made with the actuating pin 38 as shown in Figures 1 and 2 by means comprising an actuator or lever 129. Said lever has a downwardly extending arm 130 and an upwardly extending arm 131, and is pivoted at 132 to an ear 133 depending from the bottom of the bracket 53. The lever arm 130 extends downward and forward and is forked or 25 slotted at 134 at its lower end, the slot 134 being engaged by the actuating pin 38. The lever arm 131 extends upward from the pivot 132 at the front side of the bracket 53, and terminates in a laterally bent lip 135 30 which is adapted to engage with the point of a contact screw 136 projecting forward from the rocker arm 113. The upper end of the spring 124 may be anchored to this screw 136. The lever 129 is provided with a wire 35 restoring spring 137, said spring being coiled around the pivot screw or fulcrum 132 and its upper end being anchored to the bottom wall of the bracket 53 while its lower end portion is hooked over the upper 40 edge of the lever arm 130.

Associated with the escapement wheel 70, 50 72 of the rear escapement mechanism is a spring-mounted back stop 138 (Fig. 8) of ordinary construction that normally prevents backward rotation of said escapement wheel but is adapted to be cammed out of the way by the oncoming teeth 72 when the wheel turns in letter-feed direction. A similar back stop device, illustrated in Figures 55 9 and 10, is employed in connection with the forward escapement wheel 71, 73, said back stop device comprising an arm or body portion 139 terminating at one end in a yoke-like pivotal portion 140 and at the opposite 60 end in a tooth-like stop portion 141. The left-hand edge of the tooth 141 is inclined so that the tooth 141 may be cammed out of the way by the oncoming wheel teeth 73, while the opposite edge is straight so as 65 to act as a stop for the teeth 73. The par-

allel sides of the yoke-portion 140 are perforated to receive a shouldered pivot screw 142 which is secured in the top plate 2. A coiled spring 143 surrounds the shank of the screw 142 between the sides of the yoke-portion and constantly urges the tooth or stop 141 forward. A projection 144 from the yoke 140 co-operates with a stationary part 145 to limit the forward movement of the tooth or stop 141 to maintain it normally in the path of the teeth 73 so as to prevent backward turning movement of the wheel 71. When said wheel turns forward in the direction of the arrow in Figure 10, the teeth 73 will automatically cam the stop 141 out of their path.

When the space key 33 is depressed swinging the lever arms 34 downward, rocking the shaft 35 and swinging the arm 36 and the actuating pin 38 upward and forward, the movement of the pin 38 will be transmitted to the lever 129, swinging the arm 130 upward and the arm 131 rearward about the pivot 132. As the arm 131 swings rearward the contact lip 135 will engage with the contact device 136, swinging the dog rocker 111 rearward on its pivotal axis 114, 115, carrying the dog 119, 120 out of the escapement wheel 71 and the dog 122, 123 into engagement 95 with said wheel. As soon as the dog tooth 120 releases the engaged wheel tooth 73, the wheel 71 will turn under the action of the carriage power, carrying the dog 122, 123 rightward until said dog is arrested by 100 the stop 126, thus affording a stepping movement of the escapement wheel and a letter feed movement of the carriage during the depression of the space key 33. On releasing said key the dog rocker will swing back 105 on its pivots towards the front of the machine and the other parts will be restored to normal position. Thus it will be observed that the space key is effective to actuate the front reverse escapement mechanism comprising the escapement wheel 71 and the dogs 110 119, 120 and 122, 123; while the printing keys 20 are effective to actuate the rear ordinary escapement mechanism comprising the escapement wheel 70 and the dogs 99, 115 100 and 104, 105.

In operation, when one of the printing keys 20 is actuated, causing its associate type bar 7 to print and also actuating the dog rocker 91, it results in freeing the escapement wheel 70 and permitting a letter feed advance movement of the carriage. This result is brought about through the described train of connections between the escapement wheel 70 and the carriage, said train comprising the gear train 74, 90, 80, 120 the pinion carrier or support 82, the shaft 48, the feed pinion 47 and the feed rack 46. Of this train the gear wheel 74 will 125 turn on the axis 48 and the pinion 90 will 130

turn on its axis 89 as well as revolving bodily about the axis 48. The turning of the pinion 90 on its own axis will be caused by the gear wheel 80 which will be held motionless by the escapement wheel 71 in co-operation with the dog 119, 120. The teeth of the two escapement wheels 70 and 71, it should be noted, number only half as many as the teeth of the usual escapement wheels, 10 while the pinion teeth of the feed pinion 47 are of the usual number. In other words, there are half as many teeth in the escapement wheels 70 and 71 as there are in the pinion 47, to compensate for the differential 15 gearing comprising the train 74, 90 and 80. Consequently, while at each escapement movement, the escapement wheel 70 will turn twice as far as the usual escapement wheel, the pinion 47, owing to the differential 20 connection with the escapement wheel 70, will turn only the usual extent and the letter feed movement will be the regular distance. This is true also of feed movements caused by the actuations of the space bar or key, 25 which result in permitting feeding movements of the wheel 71 while the wheel 70 is held by its dog 99, 100, the connection at this time between the wheel 71 and the feed pinion 47 being made through the gear wheel 30 80, the pinion 90 and the shaft 48.

From what has been said, it will be understood that during ordinary operations of the printing keys and the space key or bar, my novel double escapement mechanism will 35 operate to afford the usual step-by-step feeding movements of the carriage from right to left. The particular advantage of my present invention will be understood from a consideration of what takes place 40 when there is an operation of the space bar, for example, before the completion of the preceding operation of one of the printing keys. The normal relationship of the escapement elements is diagrammatically illustrated in Figure 3, which shows the dog tooth 100 of the rear escapement co-operating with one of the wheel teeth 72, and the dog tooth 120 of the front escapement co-operating with one of the wheel teeth 73. 45 On depressing a printing key 20, the front escapement mechanism will not be affected but the rear dog rocker will be rocked to carry the dog tooth 100 out of engagement with the wheel tooth 72, bringing the beveled portion 105 of the dog 104 into engagement therewith. This relationship of the parts is illustrated in Fig. 4. Suppose the actuated key 20 to have been fully depressed and to have started upward, allowing the type 50 bar to recede slightly from the platen and the beveled dog to move towards the rear but not sufficiently to release the wheel tooth 72. The position of the rear escapement and of the type bar at this stage are illustrated

in Fig. 2, the corresponding diagrammatic relationship of the elements of the rear escapement mechanism being shown in Figure 5. Suppose further that at this time the space key or bar 33 be depressed to actuate the front escapement mechanism which, it will be recalled, is a reverse feed escapement. When the key 33 is actuated it will carry the tooth 120 of the fixed or holding dog rearward out of engagement with the wheel tooth 73 and bring the tooth 123 of the stepping dog 122 into engagement with said wheel tooth, affording a letter feed movement of the carriage due to the depression of the space key 33, the parts at this stage being illustrated in Figure 2 and in Figure 5. The release of the space key and its return cause the forward escapement members to assume the relationship illustrated in Figure 6, and if we assume that while there has been a further slight movement of the rear escapement elements it has not been sufficient to release the wheel then their corresponding relationship is also illustrated in Figure 6. From a consideration of this figure, it will be apparent that if now we assume that the actuated key 20 continues its upward movement sufficiently to allow the completion of the operation of the rear escapement, this will permit a letter feed movement of the carriage in addition to that resulting from the actuation of the space key. It will be seen therefore that despite the overlapping of the operations of the printing key and the space key, the escapement movements due to the actuation of the two keys will nevertheless take place just as though the key operations had been entirely separate and distinct from each other.

It will further be apparent that the same results will be attained, that is, that there will be two full and complete step-by-step feeding movements, should a printing key and a space key be depressed approximately at the same time. In such an event, the beveled pinion 90 may turn bodily on the axis 48 but with substantially no rotation on its own axis 89, said pinion acting in effect as a rigid member, transmitting movement from the shaft 48 to both of the escapement wheels 70 and 71 together.

It will be clear from what has been said that under any conditions of operation of the printing keys and space key, my invention will insure the proper spacing due to each and all key actuations, and will obviate the irregularities and imperfections in type-written matter which have heretofore resulted from uneven and irregularly timed key actuations.

It will be observed that by my invention there is provided in combination with a power driven carriage, two escapement mechanisms separately operative to feed said

carriage step-by-step, each of said escapement mechanisms comprising an escapement wheel and a pair of dogs, the two escapement wheels being constantly connected together; that the escapement mechanisms are alternately operative, one under the control of the printing keys and the other by the space key or bar of the machine; that each escapement mechanism comprises an element driven from the carriage power, and means for connecting the two power driven elements with the carriage, said connecting means comprising other elements of both of said escapement mechanisms; that in the present instance the said two power driven elements are the escapement wheels; and that the dogs comprised in each escapement mechanism are mounted on dog carriers or rockers, the two dog rockers being independently actuated and being adapted to be rocked oppositely, one affording an ordinary feed during the return stroke of a key, in the present instance a printing key, and the other affording a reverse feed during the depression of a key, in the present instance a space key.

Various changes may be made without departing from my invention.

What I claim as new and desire to secure by Letters Patent is:—

1. In a typewriting machine, the combination of a power driven carriage, and two escapement mechanisms separately operative to feed said carriage step-by-step and each comprising an escapement wheel, and a dog rocker, separate key controlled means for actuating the two dog rockers, and a common restoring spring connected to both of said dog rockers.

2. In a typewriting machine, the combination of a power driven carriage, two escapement mechanisms separately operative to afford step-by-step movements of said carriage and each comprising an escapement rack and a pair of dogs, a key for actuating one of said escapement mechanisms to give an "ordinary" feed, and another key for actuating the other escapement mechanism to give a "reverse" feed.

3. In a typewriting machine, the combination of a power driven carriage, two escapement mechanisms separately operative to afford step-by-step movements of said carriage and each comprising an escapement rack and a pair of dogs, printing keys for actuating one of said escapement mechanisms to afford a feed movement of the carriage during return strokes of the keys, and a space bar effective on the other escapement mechanism to afford a reverse feed of the carriage.

4. In a typewriting machine, the combination of a power driven carriage, two escapement mechanisms separately operative to afford step-by-step movements of said

carriage and each comprising an escapement rack and a pair of dogs, a type bar operated universal bar connected to one of said escapement mechanisms, and a space bar connected to the other of said escapement mechanisms.

5. In a typewriting machine, the combination of a power driven carriage, two escapement mechanisms each comprising a pivoted dog rocker, the two dog rockers being independently mounted, a type bar operated universal bar connected to one of said dog rockers, and a space bar connected to the other of said dog rockers.

6. In a typewriting machine, the combination of a power driven carriage, two escapement mechanisms each comprising a pivoted dog rocker, said dog rockers being independently mounted, a universal bar, a link connecting said universal bar with one of said dog rockers, key actuated type bars operative on said universal bar, a space bar frame, and a connector between said frame and the other of said dog rockers.

7. In a typewriting machine, the combination of a power driven carriage, escapement mechanisms comprising co-axial escapement wheels, each connected with said carriage, dog rockers associated with said escapement wheels, printing keys effective to actuate one of said rockers, and a space key for actuating the other rocker oppositely from the first one.

8. In a carriage feeding mechanism for typewriting machines, the combination of two separate escapement mechanisms and key controlled means for actuating one of said escapement mechanisms to afford feeding movements of the carriage on the up-stroke of the keys, and for actuating the other of said escapement mechanisms to afford feeding movements of the carriage on the down stroke of a key.

9. In a typewriting machine, the combination of two escapement wheels, a shaft on which they are supported, a feed pinion on said shaft, beveled gear wheels rigidly connected to said escapement wheels, a beveled pinion connecting said gear wheels, a support for said beveled pinion on said shaft, dogs co-operative with said escapement wheels, dog rockers on which said dogs are mounted, printing keys effective to actuate one of said dog rockers, and a space key effective to actuate the other dog rocker.

10. In a typewriting machine, the combination of a carriage, two escapement wheels, a shaft on which said wheels are supported, a feed pinion on said shaft and connected with said carriage, gearing connecting said escapement wheels and comprising an element mounted on said shaft, dogs co-operative with said escapement wheels, dog rockers for said dogs, printing keys, a universal bar operative by said printing keys

and connected to one of said dog rockers, and a space key connected to operate the other of said dog rockers.

11. The combination with the main frame 5 of a typewriting machine, of a support, a pair of escapement wheels mounted thereon, devices for connecting said escapement wheels together and also for connecting them with the carriage of the machine, 10 said wheels and said devices being mounted on said support, a second support on which

the first recited support is mounted, a pair of dog carrying rockers mounted on said second support, and an actuator for one of said rockers also mounted on said second 15 support, said second support being detachably secured to the main frame.

Signed at the borough of Manhattan, city of New York, in the county of New York and State of New York this 3rd day 20 of January, A. D. 1924.

EDWIN E. BARNEY.
